UNITED STATES PATENT OFFICE.

THOMAS B. ZELLER, OF KOSSUTH, ASSIGNOR OF ONE-FOURTH TO WILLIAM NAGLE, OF EAGLE ROCK, PENNSYLVANIA.

COMBINATION-LOCK.

SPECIFICATION forming part of Letters Patent No. 371,656, dated October 18, 1887.

Application filed August 13, 1887. Serial No. 246,891. (No model.)

To all whom it may concern:

Be it known that I, THOMAS B. ZELLER, a citizen of the United States, residing at Kos-
suth, in the county of Clarion and State of
Pennsylvania, have invented new and useful
Improvements in Combination Locks, of which
the following is a specification.

My invention relates to improvements in
combination-locks; and it consists in a certain
novel construction and arrangement of parts,
fully set forth hereinafter, and specifically
pointed out in the claims.

In the drawings, Figure 1 is a front view of
the lock. Fig. 2 is a rear view with the plate
removed to show the mechanism. Fig. 3 is a
central longitudinal section of the lock. Fig. 5
is a section on the line $x-x$, Fig. 2. Fig. 5
is a detail view of one of the disks. Fig. 6 is
a detail view of the sliding bolt.

Referring by letter to the drawings, A des-
ignates the case of the lock, in the front edge
of which is formed an opening through which
projects the nose of the sliding bolt B. The
said bolt is bifurcated at the rear end to form
the two parallel arms C C, provided with lon-
gitudinal slots c c, and the main body B of
the bolt is provided, near the front portion
thereof, with a bearing, b, adapted to align
with a slot, a, in the face of the case A.

D designates a spindle journaled in the
bearing b, and having the knob or handle D'
on the outer end, which is provided with a
flange, d, bearing against the face of the lock.

E represents a circular disk secured on the
inner end of the spindle D, and the under
portion or side of the disk is cut away to leave
a ring or annular flange, F, around the outer
edge, the outer edge of which ring is notched,
as seen at f.

G designates a stationary stud secured to
the case of the lock in direct line with the
center of the sliding bolt, and when the said bolt
is drawn back the stud passes through a rad-
ial groove, F', in the under side of the ring
or flange F, the said groove being a continua-
tion of one of the notches f. Thus the stud
passes within the flange, and if the disk is
turned so that the groove F' is out of align-
ment with the stud the bolt cannot be shot.

It will be seen that the disk can be turned en-

tirely around in either direction, the same as
if the stud were on the outside of the same.

H H are spindles journaled in bearings in
the face-plate of the lock-case, which spindles
project through the longitudinal slots c c in 55
the arms C, and they are provided on the
outer ends with handles or knobs H' H', simi-
lar to the knob D', and they are also provided
with the flanges h h, similar to the flange d. It
will be seen that when the bolt is extended or 60
withdrawn the slotted arms will slide on the
spindles H H and thus guide the motion of
the bolt.

I I are disks secured on the inner ends of
the spindles, which are similar in shape to the 65
disk E, having the annular flanges K K, pro-
vided on the outer edges with the notches
k k and in the lower side with the radial
groove K'.

L L are small studs secured rigidly to the 70
arms C C of the bolt, in line with the centers
of the disks I, and it will be seen that when
the radial grooves K' in the said disks are
aligned with the studs and the bolt is drawn
back the studs will pass through the grooves 75
and enter the open space in the interior of the
disks, thus allowing the latter to be turned
around, the same as when the bolt is shot.

It will be seen that instead of cutting out the
entire under portion of the disks, with the ex- 80
ception of the annular flanges, a narrow annu-
lar groove may be formed just within the annu-
lar flange and at the inner end of the radial
grooves. The advantage of this feature will be
evident. When the disks are so constructed 85
that when the bolt is withdrawn to open the
door the said disks cannot be rotated, because
the studs are engaged in slots or notches in the
disks, it is obvious that if a person should
glance at the combination on the face of the 90
lock he could open it as well as the owner. Thus
a careful watch must be kept on the lock at all
times while it is unlocked, or the combination
will be discovered and the safety of the lock
lost. To obviate this danger I form an annu- 95
lar groove in the underside of the disks at the
inner end of the radial groove, which admits
the stud, and thus when the bolt is retracted
the disks are free to be turned in either direc-
tion. In the drawings, instead of showing the 100

annular groove at the inner end of the radial groove, I have cut away a considerable portion of the under side of the disk, and also of the upper side, thus reducing the weight of the lock.

The width of the flange or ring on the disks depends entirely upon the throw of the bolt, the studs being adapted to be close to the outer sides of the flanges when the bolt is extended and close to the inner sides of the same when the bolt is retracted. This is to prevent all play of the bolt.

The object in notching the edges of the flanges is, that in attempting to pick the lock the studs will become engaged in the notches, and the operator will be misled to think that he has found a portion of the combination, and thus the safety of the lock is increased.

The flanges *h h* and *d*, on the operating knobs of the disks, which flanges bear and operate on the face of the lock, are provided each with a series of letters or numbers around the periphery, and indices are placed on the face of the lock to indicate the combinations. (Numbers are shown in the drawings.)

M designates a spiral spring surrounding the spindle of each of the disks and bearing at the ends, respectively, against the under side of the disks and the upper side of the slotted arm or main body of the bolt. The object of the said springs is to press the disk away from the bolt, and consequently draw the flanges *h h* firmly against the face of the lock-case, and also to prevent play of other parts of the lock.

Having thus described my invention, I claim—

1. In a lock, the combination, with the case having the slot *a*, of the sliding bolt *B*, the stationary stud *G*, the disk *E*, journaled in the bolt and having its spindle inserted through the slot *a*, the annular flange *F* at the edge of the disk, having the radial groove *F'*, whereby the said disk may be passed over the stud *G* and rotated so as to cause the said stud to contact with the inner edge of the annular flange, and means for guiding and locking the ends of the bolt, substantially as set forth.

2. In a combination lock, the combination of the sliding bolt *B*, having the rearwardly-extending parallel arms *C C*, provided with longitudinal slots *c c* and studs *L*, spindles *H H*, journaled in bearings in the case of the lock and passing through the said slots *c*, the disks *I I* on the inner ends of the said spindles, having the annular flanges or rings *K K*, equal in width to the throw of the bolt, and provided with radial grooves *K' K'*, stationary

stud *G*, in line with the center of the bolt, and the disk journaled on the bolt and having the annular flange *F*, provided with the radial groove *F'* therethrough to receive the stud *G*, substantially as and for the purpose specified.

3. In a lock, the combination, with the case having the slot *a*, of the bolt *B*, sliding in the said case and having the slotted arms *C C*, spindle *D*, journaled in a bearing in the body of the bolt and passing through the slot *a*, the handle or knob *D'* on the outer end, provided with a flange having combination letters or numerals, the disk *E* on the inner end of the spindle *D*, having the annular flange *F*, provided with a series of notches, *f*, in the periphery, and the groove *F'*, the stationary stud *G*, to pass into the said groove, the spindles *H H*, journaled in bearings in the face plate of the lock and passing through the slots in the arms *C*, respectively, the handles or knobs *H' H'* on the outer ends of the spindles, provided with flanges bearing combination letters or numerals, the disks *I I* on the inner ends of the spindles, having the flanges *K K*, provided with notches *k k* and the radial grooves *K' K'*, and the studs *L L* on the said slotted arms *C*, adapted to enter the grooves *K'*, substantially as and for the purpose specified.

4. In a combination lock, the combination of the sliding bolt *B*, having the slotted arms *C C*, spindles *H H*, journaled in the lock-case and passing through the slots in the arms *C*, disks *I I* on the inner ends of the spindles, having grooves in the under side, studs *L L* on the slotted arms to enter the grooves, handles or knobs *H'* on the outer ends of the spindles, having the flanges *h h*, bearing against the face of the lock and provided with combination letters or numbers, the spindle *D*, journaled in a bearing in the body of the bolt and moving therewith, disk *E* on the inner end of the spindle, having a groove in the under side, stationary stud *G*, to enter the groove, knob *D'* on the outer end of the spindle, having the flange *d*, bearing against the face of the lock, and the springs *M*, surrounding the spindles *D* and *H* and bearing against the under sides of the disks and the bolt, substantially as and for the purpose specified.

In testimony that I claim the foregoing as my own I have hereto affixed my signature in presence of two witnesses.

THOMAS B. ZELLER.
